UNITED STATES PATENT OFFICE.

JAMES A. DAY, OF KNOXVILLE, TENNESSEE.

SCREEN.

1,363,234.

Specification of Letters Patent. Patented Dec. 28, 1920.

Application filed February 27, 1920. Serial No. 361,789.

To all whom it may concern:

Be it known that I, JAMES A. DAY, a citizen of the United States, residing at Knoxville, in the county of Knox and State of Tennessee, have invented new and useful Improvements in Screens, of which the following is a specification.

This invention relates to apparatus for crushing or pulverizing lime-stone, rocks or other hard material and substances, and more particularly to apparatus or machines of the rotary beater type.

The invention has for its object to provide in a machine of the kind stated, a novel and improved discharge screen or grating through which the crushed or pulverized material passes, a structure being provided which permits adjustment of the screen or grating according to the desired size of the crushed particles.

The invention also has for its object to provide an adjustable screen or grating which is so constructed and arranged that the adjustment can be made from the outside of the machine, and without stopping the machine.

The objects stated are attained by means of a construction and arrangement of parts to be hereinafter described and claimed, and while the preferred embodiment of the invention has been disclosed, it will be understood that various changes and modifications may be made without a departure from the spirit and scope of the invention as claimed hereinafter.

In order that the invention may be better understood, reference is had to the accompanying drawing forming a part of this specification.

40 In the drawing,

Figure 1 is a plan view of the invention partly in section, and

Fig. 2 is a longitudinal section on the line 2—2 of Fig. 1.

45 Referring specifically to the drawing, 5 denotes the side walls of the bottom or outlet portion of a pulverizer of the type disclosed in Patent No. 1203314, dated October 31, 1916. This portion of the machine contains a screen or grating through which the lime stone or other material passes after being reduced to the proper size by the rotary beater members, the latter not being shown as they form no part of the present 50 invention.

The discharge screen or grate is composed

of a plurality of bars 6 which are wider at one end than at the other. The shape of the bars is substantially triangular and they are arranged in alternately reverse relation, the apex of one triangle being adjacent to the base of the next triangle. The bars extend transversely between the side walls 5 of the machine, and they are spaced sufficiently to permit the crushed material to pass. The spacing of the bars may be varied by moving them in the direction of their length, one bar being moved in one direction, and the next bar in the opposite direction. By reason of the shape of the bars the opposite edges thereof are arranged at oblique angles to the line of movement of the bars, and said edges are parallel. It will therefore be seen that by moving the bars in the direction of their length, the width of the spaces therebetween may be varied, and any desired width may be obtained according to the desired degree of fineness of the crushed or pulverized material.

The bars 6 are slidably supported at 80 their ends in curved slots 8 in the side walls 5, and the screen or grating is thus made concave as usual. The smaller ends of the bars are continued in the shape of guide stems 9, the opposite side edges of which 85 are parallel, said stems seating in the slots. For a short distance from their wider ends, the opposite side edges of the bars are parallel, and here the bars are spaced a distance to allow the stem of one bar to seat 90 between the two adjacent bars, the parallel edges being in sliding contact and thus serving to guide the bars when they are moved lengthwise as hereinbefore described to vary the width of the spacing. 95

On the outside of the walls 5 are outstanding ledges 10 which are flush at the top with the bottoms of the slots 8 to serve as supports for the projecting ends of the bars 6. These ledges have upstanding marginal flanges 11 at their longitudinal edges, and also upstanding end flanges 12, said flanges carrying a removable cover plate 13. The ledges and their flanges, and the cover plate form a housing for the projecting 105 ends of the bars 6, and also a cover for the slots 8 to prevent the escape of dust through said slots. Any dust settling in the housing so as to interfere with the adjustment of the bars 6, can be readily disposed of upon removal of the cover plate 13.

The longitudinal adjustment of the bars

6, to vary the spacing therebetween, is made by screws 14 threaded into nuts 15 seating non-rotatably in recesses 16 in the wider ends of the bars. The screws are rotatably supported by the flanges 11, and held against longitudinal travel by collars 17. In line with the screw receiving aperture of the nuts 15, the bars 6 have longitudinal bores 18 to seat the projecting portions of 10 the screw stems 14. Various other means may be provided for shifting the bars 6 either singly or simultaneously. The screw stems 14 are provided with hand wheels 19 or other suitable operating means.

15 The bars 6 are also provided with longitudinal discharge slots 20 through which the finer particles drop.

I claim:

1. A screen of the type described, comprising a plurality of longitudinally movable bars having longitudinal material-discharge slots, and positioned alongside each

other and spaced at their longitudinal edges, said edges being arranged at an oblique angle to the line of movement of 25 the bars to vary the width of the spaces when the bars are shifted longitudinally, and means for shifting the bars.

2. A screen of the type described, comprising a plurality of longitudinally movable bars positioned alongside each other and spaced at their longitudinal edges, said edges being arranged at an oblique angle to the line of movement of the bars to vary 30 the width of the spaces when the bars are shifted longitudinally, said bars being in sliding contact with each other at their ends, and said contiguous end portions of the bars being parallel to the path in which the bars are shiftable, and means for shifting alternate ones of the bars in opposite 35 directions.

In testimony whereof I affix my signature.

JAMES A. DAY
